UNITED STATES PATENT OFFICE.

LOUIS EARNEST WOLFF, OF JOLIET, ILLINOIS.

FOOTWEAR.

1,120,353.

Specification of Letters Patent.

Patented Dec. 8, 1914.

Application filed March 3, 1913. Serial No. 751,917.

To all whom it may concern:

Be it known that I, LOUIS E. WOLFF, a citizen of the United States, residing at Joliet, in the county of Will and State of Illinois, have invented certain new and useful Improvements in Footwear, of which the following is a specification.

My invention relates to a boot or shoe in which the upper is made of leather, or other suitable flexible material, and the bottom portion of metal; footwear of this sort being worn particularly by laborers, miners, foundrymen, and others doing rough work likely to wear out or injure boots or shoes of the ordinary sort.

The principal object of the invention is to provide a metal bottom shoe which will be very light and yet strong and durable, in which the wearing parts can be easily replaced and which, furthermore, will have a construction giving a maximum degree of comfort as well as wearing qualities.

The invention consists in certain novel improvements and constructions, to be hereinafter described and claimed, for carrying out these objects.

The invention is illustrated, in certain preferred constructions, in the accompanying drawings, wherein—

20 Figure 1 is a view, in perspective, of a shoe employing one form of the invention; Fig. 2, a sectional view taken on line 2—2 of Fig. 1; Fig. 3, a plan view of the sole of the shoe; Fig. 4, a longitudinal section of the 25 metal bottom of the shoe; Fig. 5, a modified form of metal bottom consisting of two parts hinged together; Fig. 6, a longitudinal sectional view of the construction shown in Fig. 5; Figs. 7, 8 and 9, views, in perspective, of hard metal wearing elements 30 employed in both forms of the invention illustrated in the preceding figures, and Fig. 10, a view, in perspective, of the insole heel plate.

45 Like characters of reference designate like parts in the several figures of the drawings.

Referring first to Figs. 1 to 4 inclusive, and Figs. 7 to 10 inclusive, 25 designates the upper of the shoe which may be of any desired type and may be made of any suitable material such as leather, for example. The bottom of the shoe consists of a single aluminum casting provided with hard metal wearing elements. The bottom may be said 50 to comprise a sole 26, a heel 27 and a vamp 28, these parts being integral one with the

other and the sole preferably projecting beyond the vamp as indicated at 26a. The heel is hollow, open at the top, and formed with lugs 29 for supporting the heel portion of the insole 30. The under surface of the heel is formed with the integral projection 31 which is preferably polygonal in its configuration. Secured to the undersurface of the heel, by the screws 32, for example, is a wear plate 33 (Fig. 7) having a central aperture 34 into which the projection 31 on the bottom of the heel fits. The wear plate 33 is made of some metal harder than aluminum such as cast iron, for example, and its wearing surface is roughened in some manner, for example, by forming it with the grooves 35. On the under side of the heel portion of the insole 30 is a metal plate 36 (Fig. 10), preferably made of aluminum 55 and apertured for the sake of lightness, which is secured to the insole by rivets 37 and bears upon the lugs 29. The forward portion of the vamp 28 is bent over as indicated at 38 so as to provide a protecting metal toe cap. The upper is secured to the vamp in any suitable manner, for example, by means of the rivets 39. Preferably these rivets extend through a reinforcing strip 40 which extends around the shoe within the upper. At the front end of the sole is a cast iron tip 41 (Fig. 9) secured to the sole by the screws 42 and formed with a rim 43 which extends around and protects the forward portion of the aluminum sole. Preferably removable hard metal cleats 44 (Fig. 8) are secured to the tread portion of the sole. Similar cleats 45 may, if desired, be secured to the arch of the sole. All of these hard metal wearing elements are preferably 60 attached to the aluminum casting which constitutes the body of the bottom so that they may be readily replaced when worn or broken. The main portion of the bottom of the shoe is made of aluminum because of the 65 lightness of this metal. The wearing elements are preferably made of cast iron or some other hard metal instead of aluminum so as to give the article the desired durability.

105 A modified construction is shown in Figs. 5 and 6. In this form of the invention the metal bottom consists of a front portion 46 and a back portion 47 which are hinged together preferably by an ordinary butt hinge 48. The hinge is seated in recesses formed 110 in the inner surfaces of the sole so as to be

flush with said surfaces, and is secured to the front and back portions of the bottom by screws 49. Preferably the edge of the back portion of the bottom which bears against the other member, is rounded as shown at 50 (Fig. 6). In order to keep the two parts of the bottom in alinement, except when the shoe is flexed in walking, a spring plate 51 is placed over the hinge 48 and secured at one edge by one of the screws 49.

Except in the particulars above noted, and except that in the modification of Figs. 5 and 6 the cleats 45 are omitted, the construction shown in the latter figures is the same as that shown in the first four figures, and in the drawings the corresponding parts are correspondingly numbered.

While I have described my invention in certain preferred constructions it will be understood that modifications might be made without departure from the invention.

I claim:

1. In a shoe, a cast aluminum bottom formed with a hollow heel open at the top, with its under surface and side portions integral, a vamp portion which is turned backwardly at the toe of the shoe to form a toe

cap, and a sole which projects out beyond the vamp and toe providing the shoe with an extension sole, an insole, and means for supporting the portion of the insole above the hollow heel portion of the bottom.

2. A metallic bottom for a boot or shoe, consisting of a casting forming the sole, 35 vamp and heel portions thereof, the latter portion of which is hollow, open at the top and formed with interior lugs, an insole, and a metal plate on the under side of the heel portion of said insole which fits into 40 the hollow heel portion of said casting and bears upon said lugs.

3. In a metallic bottom for a boot or shoe, the combination with a casting which forms the sole, vamp and heel portions thereof, the latter portion of which is hollow and open at the top, of an insole of soft material, and a metal plate secured to the under side of the heel portion of said insole arranged to fit within the opening of the heel portion of 50 said casting.

LOUIS EARNEST WOLFF.
